UNITED STATES PATENT OFFICE

2,494,011

CLOCK

Harold G. Stein, Milwaukee, Wis.

Application December 10, 1945, Serial No. 633,930

5 Claims. (Cl. 58—106)

1

My invention relates to clocks, and more particularly to a type of clock that may be constructed of a few parts assembled without the use of tools.

The object of my invention is to provide a clock, constructed of simple parts, assembled into a compact kit with simple instructions and directions for the assembly of the parts into a clock without the use of tools or mechanical skill.

A further object of my invention is to arrange the parts comprising the device in a manner that they may be, when assembled, actuated by means of a weight and adjusted in a manner to keep correct time.

A still further object of my invention is to provide a disassembled device that is educational in its arrangement, and assembling of the component parts thereof, the parts being simple in construction, economical in cost and easy to assemble by following simple directions.

Other and further objects of my invention will become more apparent as the description proceeds when taken in conjunction with the drawings, in which:

Figure 1 is a plan view of the face plate and the actuating parts mounted thereon.

Figure 2 is an end view of the device, shown in Figure 1, illustrating the assembly of the various parts.

Figure 3 is a front view of the auxiliary plate forming a part of the assembly and showing the parts mounted between the auxiliary plate and the face plate.

Figure 4 is a plan view of the parts mounted on the rear of the auxiliary plate which is shown in phantom.

Figure 5 is a front view of the entire device with the various parts mounted onto the front face and with the parts behind the front face and auxiliary plate shown in phantom.

Figure 6 is a front view of a modified governor bar provided with adjustment weights, and

Figure 7 is an end view of the governor bar and weights as shown in Figure 6.

Similar characters of reference indicate corresponding parts throughout the several views, and referring now to the same, the character 10 shows a face plate which is supported outwardly from the auxiliary plate 11 by means of spacers 12 which engage the plates 10 and 11, and the auxiliary plate 11 is supported by spacers 13 extending at right angle thereto when the assembled device is suspended from a vertical wall.

A drive shaft 14 provided with a drive wheel 15 on the front of the face 10 extends rearwardly

2

through the auxiliary plate 11 and supports a driven wheel 16 behind the plate 11. There is a belt 17 in the form of a rubber band leading from the peripheral surface of the driven wheel 16 over a pinion 18, which is disposed in direct alignment with the wheel 16 and which is mounted on a shaft 19 extending through both the plates 10 and 11 and journaled therein. The shaft 19 supports an escapement wheel 20 at its forward end on the front face of the plate 10. This wheel 20 is a part of the governing mechanism for regulating the speed of the clock as a unit and has a plurality of outwardly extending pegs 21 engaging its front face and extending outward at right angle therefrom. In direct vertical alignment with the shaft 19 and supported by a lower bearing 22 is a vertical shaft 23 guided near its upper end by a bearing 24. The bearings 22 and 24 extend outward from the face 10 for a sufficient distance to place the vertical shaft 23 ahead of the pegs 21 on the wheel 20 and a pair of vanes 25 and 26, attached to the shaft 23 at a pre-determined angle, extend inwardly toward the face of the wheel 20. The extreme upper end of the vertical shaft 23 supports a governor bar 27 which acts as a pendulum or governor by reciprocating back and forth. It is fastened to the upper end of the vertical shaft 23 and its motion turns the shaft 23 enough to allow the pegs 21 to escape the vanes 25 and 26 one at a time, thereby arresting the revolving of the wheel 20.

In Figures 6 and 7, I illustrate a manner in which the governor bar 27 may be provided with a plurality of notches 28 on its upper face on each side of the shaft 23. The weights are shown in the form of annular washers 29 suspended from the notches 28. These washers may be moved toward and away from the central mounting of the bar 27 on the shaft 23, thereby causing the reciprocating motion of the bar 27 to be slowed up when the washers 29 are moved toward the ends of the bar 27 and sped up when the washers 29 are brought inwardly toward the center of the bar 27.

I show these washers as a means of control but any other method may be employed to control the reciprocating motion of the governor bar 27.

A main shaft 30 is journaled through both plates 10 and 11 and supporting wheel 31 on the front face and a small pinion 32 between the plates 10 and 11. The wheel 31 acts as a reel or supply means for the cord 33 which is attached at one end to the wheel 31 and is wound around the periphery of the wheel 31 within a groove on

the peripheral edge thereof. This cord 33 extends in looped fashion over a drive wheel 15 and from it extends downward over the periphery of a pulley 34 and from it to an idler pulley 35 which is journalled on a shaft 36 and extends outward from the face plate 10.

The cord 33 is fastened at its other end to a pulley frame 37. The pulley assembly consisting of the pulley 34 and the frame 37 which supports it suspended on the cord 33 in the manner shown and are urged downward by means of a weight 38 which is disposed over the spacer on the frame 37 at 39 by means of a hook 40. This weight 38 obviously may be a solid mass of metal or the like or may be constructed in the form of a cylindrical bucket, which may be filled with sand or lead pellets, the weight of it acting as a means for driving the entire mechanism.

The shaft 30, which is journalled through both plates 10 and 11, supports a pinion 41 which in turn actuates a large wheel 42 mounted on a shaft 43, the actuation being accomplished by means of a rubber band 44 acting as a belt. On this same shaft 43 is a pinion 45 which is connected to a dial wheel 46 which is mounted to a shaft 47 by means of a rubber band 48. This dial wheel 46 mounted to the shaft 47 actuates and turns the indicator 49 on the face 10 of the clock, and acts as a hand or pointer to indicate the time on an annular dial 50 which may be in the form of a sheet of paper adhesively attached to the face plate 10 or may be directly inscribed into or onto the face plate 10. The numerals on the dial 50 are spaced into twelve hours and each hour period is divided into four periods.

In operation, the device is assembled and functions as follows:

The two plates 10 and 11 are placed in parallel relation to one another and held in spaced relation by means of the spacers 12. The spacers 13 are next placed into the apertures provided in the auxiliary plate 11 to keep the assembled device supported away from a vertical wall or the like from which it is suspended. The wheel 31 on the face 10 is turned in a counter clockwise direction by means of the projecting handle 51 which will cause the cord 33 to engage the groove on the peripheral edge of the wheel 31. In order to bring up this cord 33 the cord should be disengaged from contact with the periphery of the wheel 15. This will cause the entire weight 38 and pulley assembly 34 to be brought upward toward the face plate. When this weight is brought up to the top, the cord is looped over the wheel 15. As the weight is released, it will cause a downward pulling action which will cause the wheel 15 to revolve in a clockwise direction taking the cord from the reel or reservoir 31, and due to the idler pulley 35 it will permit the entire weight assembly to move downward. As this cord 33 is pulled downward, it will cause the wheel 15 to move in a clockwise direction, thereby turning the shaft 14 and the large wheel 16 mounted to the shaft 14 between the plates 10 and 11. A belt 17 in the form of a rubber band engages a wheel 18 mounted on a shaft 19 and this shaft 19 has the escapement wheel 20 mounted to its forward end and outside of the face plate 10.

The lower bearing 22 and the upper bearing 24 guide a vertical shaft 23 which is in direct alignment with the end of the shaft 19. The bearings extend outward from the face 10 and are supported thereby and the vertical shaft 23 has two inwardly extending vanes 25 and 26 attached thereto. These vanes are in direct

alignment with pegs shown as 21. In the illustration, there are seven of these pegs extending outward from the face of the escapement wheel 20 and the angular relation of the vanes 25 and 26 will permit a peg 21 to pass and the rotation of the wheel will be arrested by the other of the vanes. Thus, due to the belt 17, the wheels 16 will cause the shaft 19 and the escapement wheel 20 to rotate and the rotation will be controlled by this escapement movement. The top of the shaft 23 is supplied with a governor bar 27 which is of a weight and size to coordinate its movement with the weight 38 at the bottom of the cord 33.

In Figures 6 and 7, I show a pair of washers suspended in notches on the bar 27. These washers, acting as weights, control the reciprocated action of the bar 27 allowing it to move faster when they are near the shaft 23 and slowing up the action when they are far apart on the bar 27 and away from the shaft 23. The speed that the escape wheel 20 will travel will determine the revolution of a large wheel 31 mounted on a shaft 30. This wheel 31, as stated before, is the reel for the cord 33 and as the shaft 30 revolves, it will revolve a pinion 41 which in turn will revolve a large wheel 42 mounted on a shaft 43 due to its contact with the rubber band acting as a belt 44. The wheel 42 will turn the shaft 43, and a pinion 45, mounted on this shaft 43, will rotate the dial wheel 46 which is mounted on a shaft 47, which shaft is journalled in both plates 10 and 11.

On the face of the face plate 10 is a printed dial, shown as 50, spaced off, as described, into quarter hour periods and the shaft 47 has at its forward end an indicator hand, shown as 49, which indicates the time by quarter hour periods. It will be manifest to anyone that is familiar with the art that the component parts constituting the device can be made of wood or of any other suitable material, that the wheels and pulleys can be grooved at their periphery or can be made of sections of plywood or laminations to provide the groove for rubber bands or cords. By using simple directions and instructions, these parts can be assembled by anyone without the use of tools. Obviously, all shafts and apertures adopting the shafts and acting as bearings are to be of the proper dimensions and the spacers 12 and 13 would have their ends engaging the plates 10 and 11 by means of a press fit.

In the description of the device, I have shown and portrayed a single arrangement of the component parts constituting the device and show their methods of operation. I am fully cognizant of the fact, however, that in constructing this device it is possible to make many changes in the form and configuration of the parts that will in no way affect their operativeness, and I reserve the right to make such changes as I may deem convenient or necessary without departing from the spirit of my invention or the scope of the appended claims.

Having thus described my invention, what I claim and desire to secure by Letters Patent in the United States is:

1. A clock mechanism of the character described comprising in combination a face plate, an auxiliary plate, said plates disposed vertically in spaced relation to one another, a clock dial attached to the front of said face plate, a plurality of wheels of varied diameter, said wheels mounted on shafts journalled within said plates, one of said shafts provided with an indicator

hand, an escape wheel, a cord, a weight, said weight actuating said escape wheel by means of said cord, a vertical shaft, an upper and lower bearing supported by said face plate, said bearings acting as journals for said vertical shaft, said vertical shaft provided with a horizontally disposed governor bar at its upper end, a pair of inwardly extending vanes attached to said vertical shaft in angular relation to one another for contact with said escape wheel, and belt members engaging the periphery of said wheels thereby creating synchronized action of said wheels and indicator hand in relation with said dial due to the gravity actuated travel of said weight.

2. A clock mechanism of the character described comprising in combination a pair of plates, said plates spaced apart in parallel relation to one another, one of said plates provided with a clock dial, a cord, a reel for mounting said cord, a weight rotatably attached to said cord to gradually draw said cord from said reel, a plurality of wheels, a plurality of shafts, said shafts journaled in said plates, said wheels mounted to said shafts, means in the form of contact belts actuating said wheels and connecting said wheels one with the other, one of said shafts having an indicator hand, said shaft disposed at a point central to said clock dial and an escape movement provided consisting of a vertical wheel having outwardly extending members, a vertical shaft supported in direct alignment with said shaft supporting said vertical wheel, a horizontal governor bar attached to the upper end of said vertical shaft, a pair of vanes attached to said vertical shaft in angular relation to one another to permit contact of one of the projecting members on said escape wheel with said vane at a time, when urged into rotation by the weight disposed on said cord thereby producing a synchronized action of said wheels and indicator hand in relation with said dial due to the gravity actuated travel of said weight.

3. A clock mechanism of the character described in claim 2, in which the horizontal governor bar is provided with adjustably mounted weights to control the speed of the reciprocating motion of the governor bar.

4. A clock mechanism of the character described comprising in combination, a face plate, an auxiliary plate, said plates arranged in vertical relation to one another and spaced apart from one another, a clock dial attached to the front of

said face plate, a plurality of wheels of varied diameter, a plurality of shafts journaled within said plates, said wheels attached to said shafts, one of said shafts provided with indicator means, said shaft disposed centrally with said dial, another of said shafts supporting an escape wheel provided with outwardly extending members, a vertical shaft supported by said face plate in direct alignment with the shaft supporting said escape wheel, said vertical shaft provided with inwardly projecting vanes attached to said shaft in angular relation with one another and in direct alignment with the outwardly extending members on said escape wheel, a horizontally disposed governor bar attached to the upper end of said vertical shaft, a reel mounted to the end of one of said shafts, a cord disposed on said reel attached at one end to said reel, said cord arranged to contact the peripheral surface of one of said wheels acting as a drive wheel for said escape wheel, a weight, said weight rotatably supported to said cord for actuating said reel and escape movement by a force of gravity, a plurality of belts contacting the peripheral surface of said wheels, causing all of said wheels to move due to frictional contact of said belts, said wheels arranged in size to provide proper synchronized action by the escape movement and indicator on said dial, all of said wheels and plates provided with apertures of suitable dimension to accommodate said shafts for ease in assembly without the use of tools.

5. A device as described in claim 4, in which the horizontal governor bar is provided with adjustable means extending outward from the point of its attachment to said vertical shaft to permit adjustment and control of the reciprocating motion of said governor bar caused by the vanes contacting the projecting members on said escape wheel.

HAROLD G. STEIN.
